WEIGHING SCALE

Earl D. Myers, Westfield, N.J., and Samuel S. Leotta,
Jenkintown, Pa., assignors to Ohaus Scale Corporation

Filed July 1, 1971, Ser. No. 159,077

Term of patent 14 years

Int. Cl. D10—04

U.S. Cl. D52—10

FIG. 1

FIG. 2

FIG. 3

FIG. 4

FIG. 5

FIG. 1 is a front perspective view of a weighing scale showing our new design;

FIG. 2 is a left side elevational view thereof;

FIG. 3 is a rear elevational view thereof;

FIG. 4 is a perspective view, similar to FIG. 1, but showing the rotatable tower rotated 90° from the position shown in FIG. 1; and

FIG. 5 is a perspective view of a weighing scale, similar to FIGS. 1 and 4, but showing the rotatable tower rotated 45° with respect to the positions shown in FIGS. 1 and 4.

We claim:

The ornamental design for a weighing scale, as shown
